UNITED STATES PATENT OFFICE.

THOMAS C. JOHNSON, OF NEW HAVEN, CONNECTICUT, ASSIGNOR TO THE WINCHESTER REPEATING ARMS COMPANY, OF SAME PLACE.

DESIGN FOR A TEMPORARY CARTRIDGE-HOLDER.

SPECIFICATION forming part of Design No. 26,386, dated December 8, 1896.

Application filed September 23, 1896. Serial No. 606,793. Term of patent 14 years.

To all whom it may concern:

Be it known that I, THOMAS C. JOHNSON, of New Haven, in the county of New Haven and State of Connecticut, have invented a new 5 Design for a Temporary Cartridge-Holder; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a temporary cartridge-holder containing my improved design; Fig. 2, a reverse plan view thereof.

My invention relates to a design for temporary cartridge-holders employed in loading box-magazine firearms; and the design consists in the configuration shown in the accompanying illustrations and herein set forth.

The body portion A of my newly-designed cartridge-pack is U-shaped in transverse section, and tapers in side and end elevation or in width and thickness from its rear end, 25 which is closed by a wall A', to its forward end, which is open, as at A². The said body portion is virtually divided into a rear mem-

ber and a forward member by a deep and wide transversely-arranged passage A³, intersecting its closed upper edge or top and 30 extending downward nearly to its open lower edge or bottom, the end walls of the said passage being virtually straight, while its lower wall is curved and flanged. Two corresponding oppositely-projecting slightly-bowed flanges B B are located upon the opposite sides of the bottom of the body of the pack and about in line with the said passage. The rear wall A' is formed at its lower end with a rounded finger-like extension A⁴. The 40 side walls of the body portion are formed with inwardly-extending vertical corrugations a.

I claim—

The design for a temporary cartridge-holder, as herein shown and described.

In testimony whereof I have signed this specification in the presence of two subscribing witnesses.

THOMAS C. JOHNSON.
